FEELER MECHANISM FOR LOOMS.

Application filed November 17, 1924. Serial No. 750,304.

This invention relates to a feeler mechanism for looms for determining when all but a short predetermined length of yarn is removed from a bobbin in the loom and for then actuating a change mechanism to remove the empty bobbin and replace it with a full one.

Heretofore mechanical stop motions have been used for detecting when the yarn is nearly exhausted from the bobbin and for thereupon actuating the change mechanism to replace the exhausted bobbin with a full one. These mechanical change mechanisms ordinarily leave from ten to forty yards of yarn on the bobbin at the time it is removed or replaced, depending on the fineness of adjustment of the feeler mechanism. Not infrequently, with the mechanical feeler mechanism, a bobbin which is half full or even entirely full of yarn may be thrown out, in case the mechanical feeler mechanism sticks or does not function normally. In addition, these mechanical feelers tend to roughen, to some extent, the yarn, more especially when a silk yarn is used, which may frequently be damaged by a mechanical feeler mechanism.

An object of our present invention is to provide a feeler mechanism which will permit the yarn to be run off from the bobbin until only sufficient length is left to make a shuttle movement back and forth in case the change mechanism should fail to operate.

Another object of the invention is to provide a feeler mechanism which will avoid the roughening of the yarn by the movement of the feeler mechanism.

A still further object of the invention is to provide an electric feeler mechanism actuated on the closing of a circuit through a contact strip on the bobbin, contact with which is prevented by the yarn thereon until there is left only the minimum required in case a subsequent back and forth movement of the shuttle should be necessary.

With these and other objects in view, the invention comprises the apparatus described and set forth in the following specification and claims.

The various features of the invention are illustrated in the accompanying drawings, in which:

Fig. 1 is an end elevation of a portion of a loom showing a feeler apparatus and change

control mechanism embodying a preferred form of the invention,

Fig. 2 is a vertical sectional view of a portion of the apparatus taken on line 2-2 of Fig. 1,

Fig. 3 is a plan view, partly in section, of a contact feeler device and a bobbin forming a portion of the apparatus, the apparatus being shown in a position in which insufficient yarn has been removed to actuate the mechanism, and,

Fig. 4 is a plan view of a portion of the apparatus shown in Fig. 3, in a position in which sufficient yarn has been removed from the bobbin to actuate the change mechanism.

In our present invention, the actuation of the bobbin change mechanism is controlled by an electric circuit having a pair of insulated contacts mounted in position to be bridged, and thus close the circuit and actuate the change mechanism, by contact with a metallic surface on a bobbin in the shuttle as soon as this surface becomes sufficiently exposed by the removal of the proper amount of yarn. The spaced insulated contacts are so positioned relative to this bridging surface on the bobbin, which is preferably in the form of a band or ferrule at the head or base of the bobbin that a layer of yarn will remain between one of the contacts and the bridging surface, and thus prevent contact and closing of the circuit, as long as a length of yarn greater than the desired minimum remains on the bobbin.

Inasmuch as the actuation of the feeler mechanism does not depend on an accurate positioning of a mechanical element, this minimum of yarn may be gauged with exactness and nicety, so that it may be reduced to the quantity just sufficient for a subsequent back and forth movement of the shuttle in case the apparatus does not change the bobbin. The closing of the actuating circuit may serve to lock a change mechanism of any desired construction to an actuating mechanism in any desired manner and thus cause the actuation of the change mechanism.

Referring more particularly to the accompanying drawings, the invention is illustrated as applied to a loom having a bobbin magazine, indicated diagrammatically at 10, and a shuttle box 12 carried on the lay of the loom to swing backwardly and

forwardly to a position beneath the magazine as indicated in Fig. 1 and provided with an opening 13 in its forward wall through which the feeler mechanism may reach the 5 bobbin when the box swings forwardly under the magazine. A shuttle 14 of suitable form is mounted in the shuttle box 12 and is provided in its forward side with an opening 16 positioned to align with the opening 13 and give access to a bobbin 18 in the 10 shuttle.

The end of the bobbin 18 from which the last length of yarn is to be unwound is provided or covered with a metallic band 15 20 adapted to lie in alignment with the openings 13 and 16 when the shuttle box is moved towards the feeler mechanism and to be contacted by, and bridge, a pair of contacts 22 and 24 mounted in a holding 20 bracket 26 on the frame 28 of the loom in position to project through the openings 13 and 16 as the shuttle box is moved forwardly to a position beneath the magazine 10.

25 The contacts 22 and 24 are insulated from each other and are included in a changing mechanism control circuit so that, as long as they remain insulated from each other, the control circuit remains open and the 30 change mechanism is unlocked from, and unactuated by, its driving mechanism. As the bobbin 18 is brought into contact with the adjacent ends of the contacts 22 and 24, these contacts remain insulated from each 35 other as long as either of them is separated from the metal band 20 by one or more strands of yarn but when both contacts contact with the band 20 the gap between the contacts is bridged and the change mechanism 40 control circuit is closed.

When the contacts 22 and 24 are thus bridged, current flows from any suitable source, indicated diagrammatically at 30, through a wire 32 to one contact 24 and 45 from the other contact 22 through a wire 34 to a magnetic control device 36, for controlling the locking of the driving mechanism to the change operating mechanism, from which the current returns through a 50 wire 38 to the source 30. The current may be drawn from any suitable source, but as the loom is frequently operated from a power circuit, it is preferably drawn from this source, through a suitable resistance or voltage 55 reducing means where desired.

Any suitable actuating and change mechanism may be used in connection with the feeler apparatus. In the form of embodiment shown in the accompanying drawings, 60 the actuating mechanism is driven from a shaft 40 through a cam 42 which bears against one end of a lever 44 pivoted at 46 on the frame of the loom and carrying at its other end a frame 48 on which the 65 electromagnetic control device 36 is mount-

ed. The frame 48 is also provided with a collar 49 having an opening 50 through which depends a rod 52 connected at its upper end to an arm 54 rigidly mounted on a shaft 56 through which the change mechanism is operated. As the frame 48 is lifted and lowered by the action of the cam 42, the frame slides relatively to the rod 52, as long as the circuit through the control device 36 is open, a surface 58 on the frame 75 coming against a stop collar 60 on the rod 52 when the frame is in its uppermost position, at which position the bobbin is brought into contact with the contacts 22 and 24.

When sufficient thread is removed from the bobbin to enable the band 20 to contact with and bridge the contacts 22 and 24 and complete the circuit through the control device 36 a bolt 62 on the frame 48 is actuated through an arm 63 by the electromagnet device 36 to slide into a notch 64 in the rod 52, positioned to receive the bolt and thus lock the frame 48 to the rod 52 when the surface 58 abuts the collar 60. Thereupon, as the cam 42 rotates the bolt 90 62 is caught in the notch 64 and the rod 52 is drawn downwardly with the frame 48, thereby actuating the change mechanism.

As the closing of the circuit through the device 36 is only momentary, the bolt 62 is 95 withdrawn from the notch 64 when the frame again reaches its upper position by the action of a spring 66 confined between the collar 49 on the frame 48 and a collar 68 mounted on the bolt 62. The frame is 100 thereupon unlocked from the rod 52 and slides freely relative thereto until the device 36 is again operated.

Inasmuch as the actuation of the changing mechanism does not depend on an accurate 105 adjustment and accurate positioning and movement of a mechanical part, and only a light contact between the band 20 and the ends of the contacts 22 and 24 is required, the contacts 22 and 24 are so constructed as 110 to bear with slight, yielding, friction against the surface of the bobbin or of the yarn thereon regardless of the fullness of the bobbin.

For this purpose, the contacts are constructed of rods 70 and 71 slidably mounted in pairs of insulating bushings 72 and 73 on the supporting bracket 26 and urged towards the bobbin by means of encircling springs 74 and 75 confined between the bushings 72 and shoulders 76 on the rods. As the bobbins, or the yarn thereon, press against the ends of the rods 70 and 71 the springs 74 and 75 are compressed insuring a uniform contact pressure at all positions. The ends of the rods 70 and 71 may also be provided with heads 78 having stems 80 extending into sockets 82 in the ends of the rods and pressed outwardly by means of springs 84 confine between the bottoms of 130

the sockets and bottoms of the stems 80. The stems 80 may be retained in their sockets by means of transverse retaining pins 86 against which ledges 88 and 88' of the stems 5 80 are stopped.

Through the above invention a feeler apparatus is provided in which the yarn on the bobbin is only lightly touched by the feeler device so that there is no roughening 10 or injury of the yarn. The action of the feeler device is, moreover, so positive and certain that the length of thread remaining on the bobbin may be accurately governed.

As changes of construction could be made 15 within the scope of our invention it is intended that all the matter contained in the above description or shown in the accompanying drawings shall be interpreted as illustrative and not in a limiting sense.

Having thus described our invention 20 what we claim as new and desire to secure by Letters Patent is:

1. Apparatus of the type described which comprises, a bobbin having a metal surface, 25 a pair of insulated contact members mounted to be contacted and bridged by said metal surface when exposed and brought thereagainst, a bobbin change mechanism having an actuating rod and a notch in said

rod, an actuating mechanism slideable on 30 said rod and having a bolt slideable into said notch and normally retained out of said notch, an electro-magnetic means for sliding said bolt into said notch to lock said actuating mechanism to said rod, and an 35 electric circuit for said electro-magnetic means closed by the bridging of said contact members.

2. Apparatus of the type described which comprises, a bobbin change mechanism, a 40 driving means therefor, a notched transmitting rod connected to drive said bobbin change mechanism, a driving sleeve driven from said driving means and slidably mounted on said transmitting rod, a bolt in 45 said sleeve, electromagnetic means for moving said bolt into said notch to lock said driving sleeve to said transmitting rod, a bobbin having a metallic collar, a pair of insulated contact rods movable to a position 50 to contact with and be bridged by said collar and an electric circuit including said contact rods and said electromagnetic means.
